CLAIM

The ornamental design for a vegetable rack, as shown and described.

DESCRIPTION

FIG. 1 is a first perspective view of a vegetable rack showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of another state of the vegetable rack thereof;

FIG. 10 is an exploded view of the vegetable rack thereof;

FIG. 11 is an enlarged view of the selected portion 11 in FIG. 1; and,

FIG. 12 is an enlarged view of the selected portion 12 in FIG. 1.

The square and circle dash-dot-dash broken lines surrounding portions of the claimed design in FIG. 1 show boundaries of the respective enlargements depicted in FIGS. 11 and 12 and form no part of the claimed design.
